SWITCH STRUCTURE

Ray F. Lester, Syracuse, N. Y., assignor to Crouse-Hinds Company, Syracuse, N. Y., a corporation of New York

Application February 7, 1950, Serial No. 142,732

4 Claims. (Cl. 200—159)

1

This invention relates to electric switches and more particularly to switches of the type wherein the contacts are moved into and out of engagement by push button operation. Such switches are used extensively in industrial applications, the switch proper being mounted in an enclosed housing with an actuating member operable externally of the housing to effect axial movement of the stem of the switch.

When the stem of the switch has been moved axially a sufficient distance to effect engagement of the contacts of the switch, further movement of the stem would injure the mechanism of the switch. To avoid over actuation of the movable members of the switch, it has been the practice to embody mechanism in the housing between the stem of the switch and the operating manual to permit over-travel of the manual or push button without exerting any undue pressure on the movable mechanism of the switch after the contacts have been closed. These over-run mechanisms add to the size of the structure of the switch unit and materially increase the cost thereof.

In certain applications, switches of the type referred to embody an exceedingly compact structure in order that the switch proper may be mounted in a small housing and, in such instances, it is exceedingly difficult, if not impossible, to include any additional over-run mechanism.

This invention has as an object a switch of the type referred to embodying a structure within the switch proper which functions to permit over-travel of the stem member of the switch without any injurious effect on the contact mechanism, thus alleviating the necessity of any over-run mechanism between the switch and the operating manual.

The invention consists in the novel features and in the combinations and constructions herein-after set forth and claimed.

In describing this invention, reference is had to the accompanying drawings in which like characters designate corresponding parts in all the views.

Figure 1 is a vertical sectional view of a switch embodying my invention, the section being taken diametrically on a line corresponding to line 1—1, Figure 2, Figure 2.

Figure 2 is a transverse sectional view taken on line 2—2, Figure 1.

Figure 3 is a view, similar to Figure 2, taken on line 3—3, Figure 1.

Figure 4 is a vertical sectional view taken on line 4—4, Figure 3.

The switch consists of a body member 10 formed

2

of insulating material. As disclosed in the drawings, the body 10 is of cylindrical formation and is mounted in a cylindrical body 11 by being threaded therein, as disclosed in Figures 1 and 4, the body 10 forming a closure for the open end of the housing 11, and the opposite end of the housing is formed with a cylindrical boss 12. The housing 11 may be mounted in a panel 13 by positioning the boss 12 in an aperture in the panel and threading a lock nut 14 on the boss engaging the front side of the panel.

The body 10 is formed with a recess and with diametrically opposed projections 16 arranged in the recess and extending upwardly from the bottom wall thereof and terminating short of the upper end of the body. The body is also formed with a bore 17 located centrally in the bottom wall of the recess. A pair of arcuate shaped contacts 18 are fixedly mounted on the bottom wall of the recess between the projections 16. Each of the contacts 18 is fixedly secured to a metallic insert 19 moulded in the body and provided at its lower exposed end with a binding screw 20. A pair of fixed contacts 21 are mounted on the upper ends of the projections 16. The contacts 21 are secured to the upper end of metallic inserts 22 moulded in the body and being provided at their lower exposed ends with binding screws 23. The contacts 21 are also arcuate shaped and are secured to the inserts 22 by screws 24.

The pairs of contacts 18, 21 are engaged by contacts 25 carried on radially extending portions 26 of a bridge member 27. The radially extending portions 26 of the bridge member are positioned between the projections 16 of the body. The bridge member 27 is slidably mounted upon a stem 30 mounted in the body for axial movement, to move the contacts 25 carried by the bridge member alternatively into engagement with the contacts 18, 21. The contacts 18, 21 are arranged in vertical registration and the contacts 25 carried by the bridge member are movable axially in registration with the fixed contacts and so maintained inasmuch as the projections 16 prevent rotation of the bridge member 27 about the axis of the stem 30.

The stem 30 is provided with a stop to limit axial movement of the bridge member on the stem in a direction toward the bottom contacts 18. In the arrangement shown, the stem 30 is formed with a lower enlarged portion 31 slidably mounted in the bore 17 and which forms a shoulder stop against which the bridge plate 27 is positioned. The enlarged portion 31 is formed

with an axial recess in which is arranged a compression spring 33 acting between the stem and the bottom of the bore 17 and which functions to yieldingly urge the stem upwardly and the contacts 25 into engagement with the upper contacts 21.

The upper portion of the stem 30 is encircled by a sleeve 35 slidably mounted on the stem and recessed at its upper end to accommodate a compression spring 36 encircling the stem 30 and acting against the head of a screw 37 threaded into the upper end of the stem.

With this arrangement, the bridge plate 27 is yieldingly urged against the stop shoulder formed by the enlargement 31.

The stem 30 and sleeve 35 are formed of dielectric material, such as fiber. It will be apparent that upon downward axial movement of the stem 30, the bridge plate 27 is moved downwardly, moving the contacts 25 into engagement with the lower contacts 18. Upon continued downward movement of the stem 30, the bridge member 21 and the sleeve 35 slide axially upon the stem against the action of the compression spring 36, thus permitting over-running of the stem.

The stem 30 may be extended outwardly through the housing, but preferably axial movement of the stem is effected by an actuating member 40 arranged in coaxial relation with the stem and being slidably mounted in a bushing 41 threaded into the hub portion 12 of the housing. The structural arrangement described prevents damage to the bridge plate 27 in the event the actuating member 40 and stem 30 are moved inwardly after the contacts 25 have engaged the contacts 18.

It will be apparent that the structure for mounting the bridge plate on the stem is not only economical to manufacture but is confined within the switch proper and does not require any additional space within the housing in which the switch is mounted.

What I claim is:

1. A switch comprising a body formed with a recess, a pair of fixed contacts mounted in spaced relation at the bottom of said recess, a second pair of fixed contacts mounted in said recess and arranged above said first pair of contacts, a stem slidably mounted in the body for axial movement in said recess and being formed with a stop, a bridging contact slidably mounted on said stem, spring means yieldingly urging said stem to move said bridging contact into engagement with said second pair of fixed contacts, a sleeve encircling said stem and having sliding engagement with said stem and the wall portions of said recess, spring means cooperable with said stem and sleeve to yieldingly urge said sleeve against said bridging contact and the latter against said stop, and an actuating member operable to effect axial movement of said stem toward said first pair of contacts.

2. A switch comprising a body formed with a recess, a pair of contacts fixedly mounted at the bottom of said recess, a second pair of contacts fixedly mounted in said recess and being spaced axially thereof in relation to said first contacts, a stem slidably mounted in the body for axial movement in said recess and being formed with a stop, a bridging contact mounted on the stem

against said stop and being movable axially on the stem away from said stop, said movable contact having portions slidably engaging the wall of said recess and being cooperable to restrain said movable contact against rotation, a spring cooperable with said stem to yieldingly maintain said bridging contact against said second fixed contacts, a sleeve encircling the stem, spring means cooperable with said stem and sleeve to yieldingly urge said bridging contact against said stop, and an actuating member operable to effect axial movement of the stem toward said first fixed contacts.

3. A switch comprising a body formed with a recess, a pair of contacts mounted in the recess and being spaced apart axially thereof, a stem slidably mounted in the body for axial movement in said recess, a movable contact carried by the stem and being movable upon reciprocation of said stem alternately into engagement with said fixed contacts, said stem being provided with a stop and a sleeve having sliding engagement with said stem and the side wall portions of said recess, said movable contact being mounted on the stem intermediate said stop and sleeve, spring means cooperable with the stem and sleeve to yieldingly maintain said movable contact against said stop, an actuating member operable to effect axial movement of said stem in one direction, and spring means operable to effect axial movement of said stem in the opposite direction.

4. A switch comprising a body formed with a recess, a pair of lower contacts fixedly mounted in proximity to the bottom wall of said recess, a pair of upper contacts fixedly mounted in said recess above said lower contacts, a central bore formed in the bottom wall of said recess, a stem having an enlarged end portion slidably mounted in said bore, a bridging contact slidably mounted on the stem and being formed with projections slidably engaging with the side wall portions of the recess, a sleeve slidably mounted on said stem and having sliding contact with the side wall portions of the recess, spring means cooperable with said stem and sleeve to yieldingly urge said sleeve against said contact and the latter against the enlarged end portion of the stem, a second spring positioned in said bore and yieldingly urging said stem upwardly and maintaining said bridging contact in engagement with said upper contacts, and actuating means operable to effect downward movement of the stem to move said bridging contact into engagement with said lower fixed contacts.
